F. N. Barber
ATTORNEY.

UNITED STATES PATENT OFFICE.

SAMUEL E. HOPPER, OF CRAFTON, PENNSYLVANIA.

BOILER STAND.

Application filed February 10, 1926. Serial No. 87,280.

My invention relates to boiler stands.

Boilers for heating water for household purposes are supplied to the plumbing trade without any supporting structure. The boilers come each with a central tapped hole in the bottom. The plumber has to devise his own methods of supporting the boiler on fittings screwed into the said holes. It is the object of this invention to produce an assembly including a universal fitting, which will support the boiler, provide connections for a faucet or other conduit or conduits, and prevent water from entering the lower part of the stand where it will freeze in many situations. My invention also resides in the said universal fitting which is constructed to be used with a large variety of accompanying fittings, such as nipples, T's, crosses, and L's.

Referring to the accompanying drawing, the view is a central vertical section of my invention applied to a boiler, parts being in side elevation and broken away.

On the drawing 1 designates a vertical boiler having the tapped opening 2 in its bottom 3. The nipple 4 is screwed into the opening 2 and a suitable fitting, as the T 5, is screwed on the lower end of the nipple 4. The lateral opening or outlet 6 may be provided with the faucet 7 or other conduit, so that the boiler may be drained for cleaning purposes or that a supply of water may be drawn from the boiler.

My special or universal fitting 8 has the reduced threaded upper end 9 screwed into the lower end of the T fitting 5 and has preferably the shoulder 10 which engages the lower end of the T 5 when the fitting 8 is screwed as fully as possible into the T.

The lower enlarged end 11 of the fitting 8 is provided with the downwardly-open socket 12 which telescopes the leg 13 which is preferably a short length of pipe, having its lower end seated in the laterally-expanded base or foot 14. The leg 13 may be screwed into the socket 12 or not, as desired. In order to prevent water from entering the leg 13, the upper end of the socket is closed with an integral part 15 of the fitting 8. This fitting may have the portion 9 hollow as at 16 for a distance downward but not entirely through the portion 15. This hollow 16 lightens the fitting and saves some metal without material expense, as the fitting is cast.

It is seen that the fitting 8 can be attached above to a plain fitting or a T or a cross or an L or other shape, and at the bottom to any sort of a pipe or rod supported by the foot 14 or other device.

The boiler is provided with the usual heater 17 provided with the gas burner 18 and the usual water connections 19 and 20.

I claim—

In a boiler stand, a nipple for attachment to a boiler, a pipe-fitting attached to the lower end of the nipple and having a lateral opening and a vertical opening throughout its length, a faucet connected to the lateral opening, a fitting closing the lower end of the pipe-fitting and having a downwardly-open socket, a leg having its upper end in the socket, and a base supporting the lower end of the leg.

In testimony whereof, I hereunto affix my signature.

SAMUEL E. HOPPER.
